UNITED STATES PATENT OFFICE.

WILLIAM C. FERGUSON, OF FLUSHING, NEW YORK, ASSIGNOR TO GENERAL CHEMICAL COMPANY, OF NEW YORK, N. Y., A CORPORATION OF NEW YORK.

CONTACT-CHAMBER.

No. 857,389.

Specification of Letters Patent.

Patented June 18, 1907.

Application filed April 22, 1904. Serial No. 204,327.

To all whom it may concern:

Be it known that I, WILLIAM C. FERGUSON, a citizen of the United States, and a resident of Flushing, county of Queens, and State of New York, have invented certain new and useful Improvements in Contact-Chambers, of which the following is a specification.

My invention relates to contact chambers, that is, chambers adapted to contain catalytic material, such as used in the manufacture of sulfuric anhydrid and sulfuric acid according to the contact process.

My invention has for its object principally to so construct a contact chamber that the heat of the reaction going on in the chamber may be radiated into the surrounding air to a sufficient extent to keep the temperature in the contact chamber within efficient limits, and particularly prevent the temperature from rising to such a point as to necessitate the provision of special cooling devices.

Another feature of my invention is the construction of the contact chamber in such a manner that compensation may be made readily for variations of temperature in the room in which the contact chamber is placed. Obviously if the radiating surface were the same in winter as in summer, the cooling effect would be too considerable in winter, and my invention provides simple yet efficient means for regulating the extent of the radiating surface.

I will now describe two forms of my invention which have been illustrated as examples in the accompanying drawings and then the novel features of the invention will be pointed out in the appended claims.

Figures 1 and 2 are sectional elevations of two forms of my improved contact chamber; and Fig. 3 is a cross-section on line 3—3 of Fig. 2.

In carrying out my invention the contact chamber is made in the shape of a long and comparatively narrow tube within which the catalytic material is arranged in any suitable manner, as, for instance, upon supporting shelves.

In Fig. 1, A indicates the tubular body of the contact chamber, with heads A', A'', adapted to connect respectively with the inlet pipe B through which a mixture containing sulfurous acid gas and air is introduced, and with the outlet pipe B' through which

the converted gas, that is, sulfuric anhydrid, leaves the apparatus. C are the perforated shelves supporting the contact material D. The same parts are designated by the corresponding small letters in Figs. 2 and 3. It will be seen that by giving the contact chamber the shape of a long, narrow tube, the outer surface of which is exposed to the surrounding air, a very efficient cooling effect may be obtained by simple radiation. This is simply a question of proper dimensions and of a proper choice of contact material, and of the speed with which the gas is conveyed through the chamber.

As has been indicated hereinabove, conditions of temperature in the surrounding air are likely to vary considerably, and thus the radiating effect may be subject to changes which call for compensation. For this purpose I have provided means for regulating the extent of the radiating surface, so that such surface may be increased or diminished at will without, however, varying the internal arrangement, or, in other words, the volume of the contact chamber. This I accomplish by applying upon a more or less considerable portion of the exposed surface of the contact chamber a suitable non-conductor of heat to reduce radiation, as, for instance, rings of asbestos or analogous material. These non-conducting covering rings should be removable, and it is preferable to provide a set of them of relatively small height individually, so that a greater or smaller number of such rings may be applied, as desired. According to Fig. 1, the application of such non-conducting rings is greatly facilitated by providing projections or ribs A³ on the contact chamber body A, these ribs at the same time serving to increase the radiating surface and enabling the chamber to be made shorter than when the said projections or ribs are omitted. Between these projections or ribs the non-conducting rings E are placed as shown at the upper portion of Fig. 1. These rings are preferably split so that they may be removed readily, and the projections or ribs A³ I prefer to space evenly. It will be understood that when the temperature is moderate a few of these non-conducting rings will be applied to the contact chamber; should the outside temperature rise, rings will be removed; and in extreme cases the contact chamber might be

deprived entirely of the non-conducting rings. On the other hand, if the atmospheric temperature should be very low, the extent of the radiating surface will be diminished by the addition of further rings. In this manner the radiation may be regulated with such nicety that the temperature within the contact chamber, as well as the temperature of the gas leaving the same, will be practically constant. While I have shown a contact chamber of circular cross-section, it will be obvious that other shapes may be employed, if desired.

Instead of employing asbestos or analogous material to reduce radiation, I may simply use an inclosed or confined body of air. This may be accomplished, as indicated in Fig. 1, by placing one or more removable rings F between the ribs or flanges A³. To further reduce radiation, if deemed advisable, heated air may be circulated through the chamber or chambers formed by the rings F,

valved inlets F' and outlets F² being provided for this purpose.

What I claim as new and desire to secure 25 by Letters-Patent is—

1. A contact chamber for catalytic processes, provided with a heat-retaining covering of unequal effectiveness adapted to cause a different amount of radiation from different parts of the surface of said contact chamber.

2. A contact chamber for catalytic processes, combined with independently removable split rings of anti-radiating material surrounding said chamber at different points of its length.

In testimony whereof, I have signed my name to this specification in the presence of two subscribing witnesses.

WILLIAM C. FERGUSON.
